(57) CLAIM

The ornamental design for a shoe midsole, as shown and described.

DESCRIPTION

FIG. 1 is a side view of a shoe midsole showing my new design;

FIG. 2 is an opposite side view thereof; and,

FIG. 3 is a rear view thereof.

The dashed-dot-dashed lines immediately adjacent to the shaded area represent unclaimed boundaries of the design. The even dashed broken lines showing the remainder of the shoe are for environmental purposes only and form no part of the claimed design.
